Joseph T. Voorheis, Piedmont, Calif., assignor to The Coen Company, San Francisco, Calif., a corporation of California

Application June 27, 1949, Serial No. 101,661

3 Claims. (Cl. 220—55)

My invention relates to liquid straining means, particularly fuel strainers, and especially of the nature disclosed in my co-pending application filed August 20, 1948, with Serial No. 45,370.

Fuel strainers of this type include a body incorporated in a flowing fuel line and provided with a pair of alternately used fuel filters or strainers. Since the line is usually under a sub- or super-atmospheric pressure, there is provided a valving means for excluding one of the members while its filter or strainer is removed and cleaned and replaced and for then including the cleaned mechanism in the pressure line while the alternate structure is in turn serviced. Means are provided for relieving the mechanism being serviced from pressure and subsequently for restoring it to line pressure. This involves breaking or opening the seals to the mechanism, and normally requires a good deal of fastening mechanism to resist the pressures securely, to preclude leakage, and to ensure that no liquid escapes from the system or that no air unduly leaks into it in the event the pressure is negative.

It is therefore an object of my invention to provide a fuel strainer closure readily sealed against the normal positive or negative working pressure, yet in which the seal is quickly and easily broken for a servicing operation.

Another object of my invention is to provide a fuel strainer closure which can readily be removed from its normal position and can as readily be replaced in position for a continued operation.

An additional object of the invention is to provide a strainer closure in which only usual tools or in some cases no tools at all are necessary for removing and replacing the closure element.

An additional object of the invention is to provide a closure in which the parts are well protected against damage or mishandling when removed from their normal operating position.

A further object of the invention is in general to provide an improved fuel strainer closure.

Other objects together with the foregoing are attained in the embodiment of the invention described in the accompanying description and illustrated in the accompanying drawings, in which:

Figure 1 is a plan of one form of fuel strainer closure of my invention, a part of the structure, however, being disclosed in cross-section on a transverse plane.

Figure 2 is a side elevation of the structure shown in Figure 1 with a part of the mechanism being disclosed in section on a vertical plane.

Figure 3 is a part elevation and a part cross-section on the line 3—3 of Figure 1.

Figure 4 is a plan view somewhat similar to Figure 1 but showing a different form of fuel strainer closure of my invention.

Figure 5 is an end elevation of the structure shown in Figure 4 but with parts disclosed in cross-section on a transverse, vertical plane.

While the fuel strainer closure of my invention can readily be incorporated in numerous different forms depending partially on the environment in which it is to be utilized and depending partially on other design criteria, it has been successfully embodied in the two forms shown herein. In the larger form illustrated in Figures 1, 2 and 3, there is generally disclosed a fuel strainer of the sort described in detail in my mentioned co-pending application.

The fuel strainer itself preferably is intended for in-

corporation in a fuel line under a positive pressure greater than atmospheric, although it can equally well be included in a liquid line normally operating at or under atmospheric pressure. In either case, there is provided an inlet connector 5 leading into a central valve body 6, usually a complete closure provided with a removable cover 7 fastened by studs and nuts 8. Leading from the valve chamber 6 is an outlet connector 11 so that flow through the chamber is facilitated.

Preferably located at either side of the valve chamber 6 and connected thereto by conduits 12 and 13 are strainer housings 16 and 17 respectively. Since the housings are identical, a description of one of them applies equally to the other. The housing 17, for example, is preferably a circular-cylindrical fabricated body disposed with its axis 19 substantially parallel with the axis 21 of the valve chamber 6. The housing 17 at its lower end is closed by a cap 22 provided with a drain plug 23 and at its upper end terminates in a circular-cylindrical wall 24 having a machine finished circular-cylindrical interior bore 26. The position of the wall 24 is such that the housing 17 readily accommodates a filter or strainer 27 provided with a central enlargement 28 seated on a barrier wall 29 so that flow through the conduits 12 and 13 necessarily passes through the strainer to accomplish the straining function.

In particular accordance with my invention, the circular-cylindrical bore 26 is provided with a plug 31 designed to be rather freely slideable in the bore 26 and normally to be located so that the lower wall 32 of the plug serves as an abutment for a spring 33 likewise abutting the strainer 27 and serving as a positioning element. The plug 31 around its periphery is formed with a groove 34 in which a suitable sealing means 36, such as an O-ring of rubber or comparable material, is lodged. The ring 36 not only engages the plug itself but likewise engages the housing, in that it is in contact with the interior bore of the wall 24. This sealing means precludes fluid flow of any sort in either direction between the exterior and the interior of the housing.

The plug 31 is centrally extended to constitute a boss 37 projecting upwardly and being formed with a shoulder 38 at the junction of the boss and an extended hub 39. The shoulder provides a seat for a skirt 41, preferably fabricated of relatively lighter material and securely fastened to the plug after the plug has been separately made. The skirt is preferably fastened to the plug adjacent the junction of the boss 37 and the hub 39. The skirt 41 not only includes a disc-like portion overlying the end of the wall 24 but also includes a circular-cylindrical portion 42 fitting rather freely over the outside of the wall 24 and extending downwardly or axially along the wall to a slightly greater extent than does the main body of the plug 31. Thus, when the plug 31 is axially or slidably removed from its position within the housing, the exterior face of the plug adjacent the ring 36 is protected by the skirt from contact with objects which might spoil the machined surface of the ring.

The skirt 41 is also inclusive of a combined guard and handle including a pair of uprights 43 and 44 upstanding from the skirt and joined by a tube 46. This not only affords a convenient grip for a user, but also, with the uprights, serves as a guard for the mechanism spanned by it.

In order normally to hold the plug 31 in its sealing position securely against the force of different pressures outside of and within the housing, I provide the mechanism with a fastening in the shape of a U-pin 51. This conveniently comprises a rod bent upon itself to provide a hand portion 52 and a pair of legs 53 and 54 of unequal length. In addition, stops or washers 56 are welded to the legs 53 and 54 to serve as positioning abutments. The U-pin is passed through aligned apertures 57 and 58 on one side of the skirt and similar apertures on the other side of the skirt. Furthermore, the U-pin also is passed through aligned chordal apertures 59 and 61 on one side of the wall 24, these apertures being substantially in registry with the apertures 57 and 58 in the skirt. There are also comparable pin accommodating apertures on the other side of the wall in registry substantially with the apertures on that side of the skirt.

The pin 51 can readily be withdrawn from its position as shown in Figure 1, thereby freeing the plug 31 for sliding movement. By the initial insertion of the longer leg 54 into the registered apertures in the skirt and the wall, the pin can be restored to the position shown in Figure 1 with the abutments 56 stopping its motion in a convenient location. In that location, the legs of the U-pin span the plug 31 in contact with the upper surface thereof and are disposed along side of the central boss 37. Pressure within the chamber slides the plug 31 until it abuts the pin legs so that the force exerted upon the plug is transmitted to the wall of the housing. Since a large area of support is thus provided, the mechanism can be made relatively light and easy to handle. If desired, the number of legs in the U-pin can be increased by duplicating the pin in an axial direction or otherwise in order more widely to distribute the load. In any case, the plug is retained merely by the readily withdrawn pin which, when in position, provides a firm block for limiting sliding movement of the plug.

Since the housing usually operates under pressure, means are provided either for relieving the pressure within the chamber before removal of the pin 51 and the block 31, or during restoration of the parts to their operating position, for permitting air within the housing to escape as the plug is slid into position. For that reason, there is provided through the plug 31 a central or axial passageway 61 leading to an aperture 62 of small cross-sectional area, flow through which is controlled by a screw needle valve 63 provided with a thumb piece 64. An outlet 66 from the passage passes through the side of the hub 39. The user, by manipulating the screw 63, opens or closes the passageway 61 so that the pressure within the chamber can be equalized with the atmosphere just prior to or during movement of the plug 31.

Since the housings 16 and 17 are used alternately, there is provided a means for preventing the opening of the particular housing which is immediately in use in the liquid line. This means is similar to that shown in my co-pending application and in general includes an extensible member 71 having a screw component 72 for adjusting its length. One end of the extensible member is formed as a ring 73 which can be slipped over the hub 39 whereas the other end is somewhat loosely connected by a pin 74 to a radial arm 76 controlling the operation of the valving structure 77 within the valve chamber 6. Since this structure is not part of the present invention, it is not described in detail. It operates to isolate either one or the other of the chambers 16 and 17, and in order that the valving interconnection can be changed, it is first necessary to remove the ring 73 of the extensible member from the hub 39. This makes it impossible to remove the plug 31 from a chamber until and unless that chamber has previously been put out of communication with the liquid line.

In the modification of the invention shown in Figures 4 and 5 the structure is comparable except that a different type of valving mechanism is utilized and the parts are somewhat smaller and lighter. In this arrangement, the two strainer housings 81 and 82 are placed in communication with the inlet 83 and the outlet 84 of the line by means of a plug cock 86 controlled by a handle 87 at the lower extremity of the assembly. A radial arm 88 mounted on the upper extension 89 of the cock is provided with an extensible mechanism 91 for engagement with either one or the other of the hubs 92 of the closures. The construction of the chambers themselves is otherwise substantially identical with that shown in the previous modification as is that of the filters or strainers. A pressure spring 93 contacting the lower face of the plug 96 holds the filter or strainer in place.

In both forms of the fuel strainer closure disclosed herein, there is provided a means for sealing the housings without likelihood of leakage in ordinary service, yet in which by the simple withdrawal of the plug from the housing or casing, the mechanism is laid open for easy removal of the strainer. The parts can as readily be restored in the reverse order. The use of special wrenches or tools is obviated, and the time involved in servicing the trainers is reduced. Additionally, the cost of manufacture is favorable and the operating characteristics of the mechanism are improved.

I claim:

1. A fuel strainer closure comprising a strainer housing having an outlet defined by a cylindrical body having an axial cylindrical bore therein, said body having a plurality of pairs of aligned chordal apertures adjacent its outer end, a plug slidably in said bore, said plug having an annular groove around its periphery, a sealing device in said groove engaging the wall of said bore, a boss on the outer face of said plug, a skirt secured to the outer end of said boss and extending across said bore and around the outer end of said body, said skirt having apertures therein aligned with said pairs of chordal apertures, and a U-pin having a pair of parallel legs passing through respective ones of said aligned apertures and spanning said bore for blocking outward sliding movement of said plug.
2. A fuel strainer closure comprising a strainer housing having an outlet defined by a cylindrical body having an axial cylindrical bore therein, said body having chordal apertures therein near its outer end, a plug slidably in said bore, said plug having an annular groove around its periphery, an O-ring in said groove engaging the wall of said bore, a boss on the outer face of said plug, a skirt secured on the outer end of said boss and encompassing said wall, said skirt having apertures therein aligned with said chordal apertures, and a U-pin passing through all of said apertures and spanning said bore alongside said boss for blocking outward sliding movement of said plug.
3. A rapidly operable closure arrangement comprising a cylindrical body having an axial cylindrical bore therein, said body being open at one end and having a plurality of pairs of aligned chordal apertures near said end, a closure plug slidably disposed in said bore, said closure plug having a deformable sealing means about its periphery engaging said bore, and a U-pin having a pair of parallel legs passing through said aligned chordal apertures and spanning said bore outwardly of said plug whereby said closure plug is blocked from outward sliding movement.
